UNITED STATES PATENT OFFICE.

JOHN M. CONLEY, OF GOLCONDA, ILLINOIS.

WIRE-STRETCHER.

1,176,882.

Specification of Letters Patent. Patented Mar. 28, 1916.

Application filed March 10, 1915. Serial No. 13,410.

To all whom it may concern:

Be it known that I, JOHN M. CONLEY, a citizen of the United States, residing at Golconda, in the county of Pope and State of Illinois, have invented a new and useful Wire-Stretcher, of which the following is a specification.

This invention relates to wire stretchers, and aims to provide a novel and improved device of that character.

It is the object of the present invention to provide a wire stretcher of unique construction, whereby its utility is enhanced.

Another object is to provide a wire stretcher which may be utilized for stretching a fence wire past a post to which it is to be secured.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

The preferred embodiment of the invention has been illustrated in the accompanying drawings, wherein:

Figure 1 is a side elevation of the improved wire stretcher in use. Fig. 2 is a similar view showing how the structure is utilized in stretching the fence wires beyond the post to which they are to be secured.

Fig. 3 is a side elevation illustrating the use of the device as a jack or post puller. Fig. 4 is an enlarged fragmental view of the device. Fig. 5 is a cross sectional view taken on the line 5—5 of Fig. 1. Fig. 6 is a plan view of the device as used in the same capacity as shown in Fig. 2.

The stretcher includes a bar 6, through which are driven pins 7 to form studs upon the opposite sides of the bar. The pins or studs project substantially equal distances from the respective sides of the bar and are arranged in two series A and A' parallel with and spaced from the edges of the bar. The pins or studs of the two series are in staggered relation.

A lever 8 has a fork 9 at one end straddling the bar 6. The width of the fork arms is such that the same will at all times contact with or ride upon at least two pins or studs, thus preventing the fork arms from

dropping between or interlocking with the pins or studs, and enabling the fork 9 to successfully ride along the bar.

Pawls or dogs 10 have their butt ends fulcrumed upon pivot pins 11 secured through the arms of the fork 9 at the opposite edges of the bar 6. The pawls 10 are of U-shaped cross section so as to straddle the edges of the bar 6 and have the flanges 12 snugly engaging the sides of the bar to prevent the pawls from flexing to one side or the other. The pins 11 are engaged through the basal ends of the flanges 12. The flanges 12 are provided at the free ends of the pawls with the hooks 13 engageable with the respective pins or studs 7. The outer edges of the hooks 13 are curved to form cams 13' for causing the hooks to snap over the pins or studs 7.

The pawls 10 are spring pressed by means of wire springs 14 having their intermediate portions coiled around the pins 11, each spring 14 having one of its arms engaged through the intermediate portion of the corresponding pawl 10, as at 15, and having its other end hooked around or engaged to a pin or rivet 16 secured through the arms of the fork 9 at the corresponding side of the bar 6. The springs 14 tend to swing the free ends of the pawls inwardly or toward the pins or studs 7, and the intermediate portions of the pawls bearing or riding against the edges of the bars 6, limit the inward movement of the hooks 13, so that the cams 13' will coöperate properly with the pins or studs 7. The arms of the fork 9 are provided with outstanding apertured ears 17 intermediate the edges of the bar 6, and chains 18 are secured to the ears 17, and have terminal hooks 19. A chain 20 is secured to one end of the bar 6, the said end of the bar being preferably curved, as at 21.

In the use of the device as illustrated in Fig. 1, the end 21 of the bar 6 may be anchored to a post P by passing the chain 20 therearound and engaging the hook 20^a at the free end of the chain 20 with one of the links of the chain 20 after the said chain has been wrapped around the post. The chains 18 may then be passed around a fence clamp C and the hooks 19 engaged to the proper links of the chains 18, in which event the handle or lever 8 may be oscillated to stretch the wires W attached to the clamp C. As the handle or lever 8 is oscillated,

the cams 13' of the hooks 13 will cause the hooks to alternately snap over the pins or studs 7 of the two series A and A' whereby the lever 8 will be advanced along the bar 6 to stretch the wires W.

As illustrated in Fig. 3, the device may be employed as jack or fence post extractor, and to this end the bar 6 may be set on end so that the chains 18 may be passed around the post to raise the same as the lever 8 is raised due to its oscillation.

As illustrated in Figs. 2 and 6, the device may be employed for stretching the wires W beyond the post P' to which the wires 15 W are to be secured. Thus, that end of the bar 6 remote from the end 21, may be set against the post P' and hooks 22 engaged around the post P' at that side opposite the wires W, the hooks 22 having eyes 22^a 20 at the ends of their shanks for engaging the proper pins or studs 7 for attaching the hooks to the bar 6. Thus, the hooks 22 will resist the tendency of the bar 6 to swing

around the post P', due to the tension of the wires W, and the hooks 22 will also 25 assist in holding the bar 6 in place against the post.

Having thus described the invention, what is claimed as new is:—

In a device of the character described, a 30 bar having studs projecting from its sides and adjacent its edges, a lever having a fork straddling the bar, and pawls of U-shaped cross section pivoted within the fork at the opposite edges of the bar and straddling 35 the said edges thereof, the flanges of the pawls having hooks at the free ends of the pawls engageable with the said studs.

In testimony that I claim the foregoing as my own, I have hereto affixed my signature in the presence of two witnesses.

JOHN M. CONLEY.
